CONDUCTOR CLAMP

L. E. Lindsey, 222 Vista Ave., Pasadena, Calif. 91107

Filed Apr. 10, 1967, Ser. No. 6,613

Term of patent 14 years

(Cl. D26—1)

FIGURE 1 is a perspective view of a conductor clamp embodying my new design;

FIGURE 2 is a perspective view of my conductor clamp taken from the opposite side thereof; and

FIGURE 3 is a cross-sectional view taken along line 3—3 on FIGURE 1.

The fragmentary broken-line showing of the outer end of an insulator and a supporting bracket for the conductor clamp is for illustrative purposes only.

I claim:

The ornamental design for a conductor clamp, as shown and described.
